UNITED STATES PATENT OFFICE

2,596,338

PRINTING SLUG SLICING AND SHAVING MACHINE

James Dobbie Lithgow, Hamilton,
Ontario, CanadaApplication July 16, 1948, Serial No. 38,985
In Canada July 23, 1947

2 Claims. (Cl. 29—24)

1

My invention relates to a machine for slicing and shaving lead printing slugs, and the object of my invention is to provide a machine wherein the type carrying face of a slug may be sliced from the main body of the slug and such slice shaved to the correct height whereby it may be immediately placed upon the top of a build-up slug within a type set-up without the necessity of making any further height adjustment to bring its type face to the level of the faces of the rest of the type assembly.

In printing practice, as in the production of newspapers, the type face is cast upon the face of lead slugs which are in the vicinity of one inch high, and the slugs are assembled and locked up to make the forme. The matrix flong is produced from the forme, and the printing plate cast from the matrix flong.

It will be appreciated by those skilled in the art, that in standard practice, large slugs such as advertising copy, are very often quite heavy and awkward to handle, and furthermore, where inserts have to be made, it is necessary to cut out portions of the slug through its entire thickness for the reception of the insert slug which then has to be aligned and wedged in place, which steps of necessity take valuable time, when meeting the deadline in newspaper printing.

The object of this invention is to simplify the work entailed in alterations or adjustments in slugs or their arrangements, and to attain this end, I in certain cases, slice the type carrying face from off the slug and provide build-up slugs upon which the type carrying slices rest, the combination height of the type carrying slice and the build-up slug being equal to the height of a standard type carrying slug. To carry out this operation I provide a machine adapted to grip a slug and pass it through a saw whereby the type carrying slice is cut off, and to then pass the cut face of such slice across a shaving blade whereby any saw cut irregularities are removed and the slice brought to the exact height.

A further object of my invention is to furnish a machine wherein the slug is supported upon a reciprocable member, the saw being positioned in the path of such member in one direction of its movement whereby the slice is cut off. The slug shaving blade engages the cut surface of the slice in the other direction of the member's movement.

With the foregoing and other objects in view, as shall hereinafter appear, my invention consists of a printing slug slicing and shaving machine all as hereinafter more particularly de-

2

scribed and illustrated in the accompanying drawings in which:

Fig. 1 is a front elevational view of my machine.

Fig. 2 is an end elevational view thereof.

Fig. 3 is a vertical longitudinal cross-sectional view through the portion of the machine carrying the saw and shaving blade, and showing the slug mounted thereon and passing into engagement with the saw, as indicated by the arrow.

Fig. 4 is a similar view to Fig. 3 showing the completion of the slicing of the slug by the saw.

Fig. 5 is a similar view to Fig. 3 showing the cut off portion of the slug removed and the remaining slug slice being shaved by the blade in the return movement as indicated by the arrow.

Fig. 6 is a plan view of a type slug.

Fig. 7 is a side elevational view thereof, and

Fig. 8 is a side elevational view of the slice after it has been cut away from the slug along the dotted line shown in Fig. 7.

Like characters of reference indicate corresponding parts in the different views of the drawing.

While my invention fills a very definite need in the printing industry, it is simple in construction and in operation. The machine as illustrated in Figs. 1 and 2 is carried upon a suitable supporting frame, which is not shown, and consists of a bed plate 2 having a longitudinal groove 3 therein, within which a vice 4 is slidably contained. The vice 4 is formed with a moveable jaw 5 which is actuated in clamping relation to the back portion 6 of the vice by a screw 7 which is threaded into the back portion 6 and carries a knurled knob 8 on its outer end.

The vice 4 is designed to travel to and fro on the bed plate 2 under the influence of a travelling nut which is carried upon a screw operated by a handle 9. The particular fitment of the nut and screw assembly is not shown as this construction follows standard machine tool practice.

A circular saw 10 is positioned above the upper face of the vice at one end thereof and is provided to engage a slug carried in the vice when the vice is moved towards and underneath the saw. The saw is carried upon the upper end of a vertical spindle 11, the lower end of which spindle carries a V-belt pulley 12 connected by a V-belt 13 to a pulley 14 on an electric motor 15.

A vertical bracket 16 extends upwardly from the bed plate 2 and is furnished to carry the shaving blade mechanism. A pair of bearings 17 and 18 are mounted upon the upper face of the bracket and carry a spindle 19 upon the forward end of which a disc 20 is eccentrically

mounted. A collar 21 encircles the disc 20 and is rotatable thereon. An operating handle 22 extends radially from the spindle 19 and by means of which the spindle may be turned within its bearings.

The forward face of the bracket 16 carries a blade supporting member 23 which is vertically slidable thereon, and the member 23 is linked to the collar 21 by a threaded rod 24. The upper end of the rod 24 is pivotally connected to the collar 21 and its lower end pivotally connected to the member 23. As the disc 20, carrying the collar 21, is eccentrically mounted upon the spindle 19, partial rotation of the spindle 19 will cause the slidable member 23 to move downwardly into the position shown in Fig. 1.

The slidable member 23 carries a shaving blade 25, which is supported at a suitable inclination at one end of the member 23 by means of a pair of set screws 26 passing through slots 27 in the blade and threaded into the member 23.

In order to provide the necessary adjustments of height of the slidable blade carrying member 23, the lower end of the link rod 24 is threaded into a pivotal connection in the member 23, and the upper end of the rod is threaded into a pivotal connection in the collar 21, so that rotation of the rod 24 by means of its knurled knob 28 moves the slidable member 23 either towards or away from the collar 21. The link rod 24 is secured in its adjusted position by a lock nut 29.

When a slug 30 such as illustrated in Fig. 7 is being sliced, it is placed with its type face 31 resting upon the surface 32 of the vice. The vice jaw 5 is then tightened up by turning the knob 8 and screw 7 so that the slug is tightly gripped. The motor 15 is then switched-on to rotate the circular saw 10 and the vice is made to travel along the bed plate 2, under the action of rotating the handle 9, so that the saw engages the end of the slug as illustrated in Figs. 1 and 3. The travelling movement of the vice is continued until the slug has been sawn through, as illustrated in Fig. 4. During this operation the slide block 22 is in the uppermost position as illustrated in Fig. 1, that is with the shaving blade 25 clear of the slug.

When the slug has been sliced the motor and saw are stopped and the sawed off portion 30A, as shown in Fig. 4, is lifted off and disposed of. The handle 22 is then swung in a counter-clockwise direction whereby the spindle 19 and disc 20 are rotated. As the disc 20 is positioned eccentrically upon the spindle 19 its rotation will move the collar 21 downwardly, thus the sliding member 23 will be also moved downwardly through the medium of the link rod 24. When the slidable member 23 has been moved downwardly to the fullest extent, the cutting edge of the shaving blade will be in a position to shave the slice remaining in the vice to the correct height.

To carry out the shaving operation the handle 9 is turned to travel the vice towards the blade whereby the edge of the blade will engage and shave the top of the slice, as illustrated in Fig. 5. When this operation is completed the vice is loosened and the slice which carries the type is now ready for fitment within the forme. In positioning the slice within the forme it is laid upon the top of a build-up slug, the height of

which in combination with the height of the slice is the same as the height of the other slugs in the forme so that no further adjusting is necessary. The slice can be readily anchored in place through the use of adhesive tape or by any similar quick adhesive method. When the shaving operation is completed it is only necessary to turn the handle 22 in a clockwise direction whereby the slidable member 23 and blade 25 are lifted to their uppermost position, at which time another slug can be locked in the vice and another slicing and shaving operation carried out.

From the foregoing description, it will be apparent that I have devised a very simple and practical machine for slicing and shaving printing slugs and although I have shown a particular embodiment of my invention it is to be understood that I may make such changes and alterations as I may at any time deem necessary without departing from the spirit of my invention as set forth in the appended claims.

What I claim as my invention is:

1. A combined slug slicing and shaving machine comprising a reciprocable slug gripping vice, means for reciprocating the vice in successive forward and return directions in the same plane, a saw positioned above the vice and in the path of forward movement of a slug contained in the vice to transversely saw a slice from the slug lengthwise during said forward movement with the slice remaining gripped on the vice, a slidable member, a shaving blade carried upon the slidable member, a member extending at right angles to the path of travel of the vice and upon which the shaving blade slidable member is mounted, a rotatable mechanism for actuating the shaving blade slidable member, a link rod extending from the rotatable mechanism to the shaving blade slidable member, and means for adjusting the length of the link rod.

2. A combined slug slicing and shaving machine comprising a reciprocable slug gripping vice, means for reciprocating the vice in successive forward and return directions in the same plane, a saw positioned above the vice and in the path of forward movement of a slug contained in the vice to transversely saw a slice from the slug lengthwise during said forward movement with the slice remaining gripped on the vice, a slidable member, a shaving blade carried upon the slidable member, a member extending at right angles to the path of travel of the vice and upon which the shaving blade slidable member is mounted, a rotatable eccentric mechanism for actuating the shaving blade slidable member, a link rod extending from the rotatable mechanism to the shaving blade slidable member, and threaded means for adjusting the length of the link rod.

JAMES DOBBIE LITHGOW.
